UNITED STATES PATENT OFFICE

130,065

DESIGN FOR A FOLDING BOTTLE CARRIER

Frank Di Rico and Angelo Libertine, Quincy, Mass., assignors to Hub Folding Box Co., Boston, Mass., a firm composed of Frank Di Rico and Angelo Libertine

Application May 28, 1941, Serial No. 101,210

Term of patent 14 years

To all whom it may concern:

Be it known that we, Frank Di Rico and Angelo Libertine, citizens of the United States and residents of Quincy, county of Norfolk, and State of Massachusetts, have invented a new, original, and ornamental Design for a Folding Bottle Carrier, of which the following is a specification, reference being had to the accompanying drawing, forming a part thereof.

The figure is a perspective view of the folding bottle carrier, in initial bottle-receiving condition, showing our new design.

We claim:

The ornamental design for a folding bottle carrier, substantially as shown.

FRANK DI RICO.
ANGELO LIBERTINE.
